UNITED STATES PATENT OFFICE.

MAX SCHEY, OF BROOKLYN, NEW YORK.

HEATING ELEMENT.

1,422,379.

Specification of Letters Patent.

Patented July 11, 1922.

Application filed August 29, 1921. Serial No. 496,263.

To all whom it may concern:

Be it known that I, MAX SCHEY, a citizen of the United States, residing at New York city, borough of Brooklyn, county of Kings, 5 and State of New York, have invented a certain new and useful Heating Element, of which the following is a specification.

This invention is a heating element adapted particularly for "rotisseries", the name 10 applied to the well known broiling apparatus made under Patent No. 902,724 of George Giovanna.

Rotisseries of the character specified embody a plurality of spits arranged one above 15 the other and extending in horizontal position before an upright or vertical heating element, constituting the source of radiant heat, which is employed for the roasting or broiling of meats supported on the spits. 20 The Giovanna patent referred to shows a coal fire back of a vertical grate to furnish heat for roasting meats supported on spits positioned forwardly thereof and one above the other. This method of broiling was 25 practised for a number of years, but, as coal fires give off objectionable gases, smoke, require proper drafts, and are difficult to maintain at a proper temperature, a series of experiments were carried out to the end that 30 gas might be adopted as a fuel, in lieu of the coal.

These experimentations, which I carried out, with the problem under consideration lead me to the conclusion that for efficient 35 broiling, the best results can be obtained through the employment of a radiant and preferably radiated heat and not by the direct heat of a flame. Having come to this conclusion, experiments were carried out 40 with heating elements embodying asbestos fibre or asbestos wool, as it is sometimes called. This wool or fibre was tufted on the face of a plate provided with perforations through which the gas found exit and burned 45 on the face of the plate, the object being to raise the asbestos fibre to a high temperature, so that the heat thereof might be radiated and such radiated heat employed for the cooking operation. Such a structure 50 was found, when new, to give superior results in effecting a relatively slow cooking and simultaneous broiling or browning of the meats.

It was found, however, that since the heating element for a broiler is more or less directly subjected to fat from the roasts which

is splashed or otherwise comes in contact with the heating element, that after a relatively short time, the asbestos wool or fibre became more or less impregnated with such 60 fat, which seemed to act as an insulator with the result that such fibre did not heat properly and consequently did not radiate the heat to efficiently effect the cooking operation. Moreover, such fat impregnated fibre 65 emitted objectionable odors and smoke which are highly detrimental.

With asbestos fibre, it was practically impossible to clean or free the same from the fatty content, and, accordingly, asbestos 70 fibre for the purpose specified has proven impractical.

With these considerations in mind, the present invention embodies, in its broadest aspect, the use of hardened plastic mineral 75 earth as a radiating medium for heat applied directly thereto and experience has shown that when this material is used in the making of a rotisserie burner, that high efficiency in heat radiation is accomplished 80 and at the same time the burner retains such efficiency, even though it be spattered with fat. Moreover, fat may be readily removed from the burner by cleaning the same, since the mineral earth is relatively non-porous, 85 so that the soaking of the fat into the material is not possible.

In practically carrying out the invention, I preferably employ what is known in the trade as asbestos wood as a backing or foundation for the burner. This asbestos wood is a combination of asbestos, cement, and a suitable binder and is a commercial product employed in the building trades for other uses. It is hard and rigid and is not apt 95 to sag, warp or twist under heat. On the face of this plate, which is preferably stippled or roughened, are molded parallel, horizontal ribs or ridges of plastic mineral earth, sometimes known to the trade as retort cement, because of its well known properties of resisting heat which recommends it for use as a lining for retorts, wherein it serves to protect the metallic wall of the retort from the direct action of the heat. 100 These parallel ribs are molded directly on one face of the asbestos wood plate and while in plastic form, are preferably gone over with a sharp implement or trowel and fashioned into uneven surfaces or sharp 105 irregularities or points, which, in the operation of the burner, are adapted to be heated.

to a high temperature, and, because of their relatively large superficial area effect a maximum radiation of such heat.

Across the back of the plate and in spaced relation thereto is a metal plate forming between said plate and the face plate of the burner a gas chamber into which gas is introduced and from which it flows through rows of perforations positioned between the 10 ribs or ridges of the mineral earth on the front of said plate. The gas burns forwardly of the plate at each perforation in a small blue flame, which serves to heat the mineral earth for the purposes specified.

15 The invention embodies further features of construction, which are important in the practical operation of the burner and these features will be clearly brought out in the following detailed description and in the appended claims.

15 The accompanying drawings illustrate one practical embodiment of the invention, but the construction therein shown is to be understood as illustrative, only, and not as defining the limits of the invention.

Figure 1 is a front elevation of one lateral half of a burner embodying the present invention.

Figure 2 is a back elevation of the structure shown in Figure 1.

Figure 3 is a central section perspective of the burner; and,

Figure 4 is a true section on the line 4—4 of Figure 2.

35 Referring to the drawings, 1 designates the front plate of a burner, which may be generally referred to as fire-proof, non-metallic and rigid. It may satisfactorily embody a slab of asbestos wood, the name given 40 by the building trades to slabs of composition cement and asbestos commonly used in such trades for partitions, walls, ceilings, etc., as a backing for plaster. This material is fire-proof and very rigid and does not 45 twist or warp under heat.

In the back of the face plate 1 is positioned a back plate 2 preferably of metal and off-set intermediate its margins to form a gas chamber 3, into which gas may be introduced through an inlet nipple 4, secured to the back plate by rivets 5. The marginal portions of the back plate 2 are adapted for face engagement with the back of the front plate 1 and a U-shaped binding 6 embraces the margins of both the front and back plates, throughout the four sides of the burner, for the purpose of binding the parts firmly together, so that they may be handled as a unit.

60 Formed in the front plate 1 are a plurality of perforations 7. These perforations are arranged in horizontal rows extending transversely of the burner and spaced apart vertically. They are preferably formed by 65 drilling the plate 1, and, in practice, I find

that they will function to greater advantage if each perforation is countersunk at its back as shown at 8, since when so formed there is less liability of choking the perforations, which are necessarily quite small, by 70 impurities which may be carried in suspension by the gas, and, furthermore, lint or particles of asbestos will not serve to close the perforations so readily as would be the case if the holes were drilled straight 75 through for the full thickness of the plate. The countersinking of the perforations has been found in practice to obviate considerable trouble ordinarily experienced.

Extending horizontally across the face of 80 the plate 1 and intermediate the successive rows of perforations 7 are molded ribs 9. These ribs are formed from plastic mineral earth, known to the trade as retort cement, and generally used to line the metallic casings of retorts, so as to protect them against the direct action of the fire. The mineral earth is applied to the face of the plate 1 in a plastic condition and the face of said plate is preferably roughened or stippled so 90 as to permit of a proper bond with the plastic material. The ribs 9, after being molded, or otherwise applied to the plate 1, are roughened in any suitable manner, such for example as by a sharp instrument so 95 that the surfaces will be uneven and preferably bristling with sharp projections or points giving a very irregular and uneven appearance. The effect of this operation is to impart to the ribs maximum superficial 100 area and at the same time provide through the employment of sharp points and knife-like edges for maximum radiation.

After the ribs are applied in the manner described, they are allowed to harden 105 and thereafter become extremely hard and non-porous.

With the construction described, the gas is introduced into the chamber 3, issues from the perforations 7 and burns with a blue 110 flame forwardly of the face plate. These small blue flames raise the ribs 9 to a high temperature, the heat whereof is radiated to the meats supported on spits forwardly of the burner which stand in upright, substantially vertical position.

In practice, the gas pressure is so regulated that the flames are maintained relatively small and just sufficient to properly heat the ribs 9, so that the heat applied to 120 the roasts is purely a radiated heat and is in every respect a radiant heat. Accordingly, the roasts are not burned as would apt to be the case through a direct heat, but, in contradistinction, are baked through by 125 the time their outer surface has acquired the desirable rich brown color.

It will be noted particularly from Figures 2 and 3 of the drawings, that the gas is introduced into the gas chamber at the lower 130

portion thereof, and it is found, in practice, that it has a tendency to rapidly rise in the chamber and flow with the greatest force through the upper rows of perforations. I have discovered, however, that if wire gauge screens are positioned across the gas chamber, so as to extend horizontally, they form barriers to the gas which serve to retard the upward flow thereof, so that the gas is applied in equal quantities and under an equal pressure to all rows of perforations. These screens are designated 10 in the drawings, and while they may be secured in position in any suitable manner, they are preferably held in place by bolts 11, which pass through the face plate and through the back plate, after the manner best shown in Figure 3.

A further advantage in the employment of the screens 10 is that they preclude flash-backs of fire, since the flash-backs will not occur through a wire screen. They further serve to free the gas of impurities carried in suspension therein. The lowermost screen is preferably downwardly extended to such degree as to cover the feed nipple 4, as best shown in Figure 3, so as to strain the incoming gas.

The purpose of the bolts 11 is to rigidly tie together the front and back plates inwardly of their margins and a spacing member 12 preferably surrounds each bolt between the plates, so as to maintain said plates at all times in proper spaced parallel relation.

In some of the prior burners placed on the market, the front plate has been formed of relatively pliable asbestos, which, when subjected to heat, expanded and warped usually in the direction of the back plate, so that the gas chamber was not of uniform depth throughout. This condition effected an uneven distribution of the gas due to venturi principles, but it will be manifest from the foregoing description of the present invention that this cannot occur in the construction described, not only because of the introduction thereinto of spacers, but also because of the rigid character of the face plate 1. In practice, the bolts 11 are preferably stove bolts with countersunk heads and are so positioned that their heads will lie beneath and be covered by the ribs 9, so that they are properly protected from the heat and will not be unduly subject to expansion.

One of the most deleterious conditions surrounding prior burners is that after they have operated a short time, they become more or less blanketed by floating gases due to improper or incomplete combustion. These gases which usually are of the poisonous variety, blanket the face of the burner, against the inflow of pure air which it is required to effect complete combustion, during the continued operation of the burner,

and produce relatively long yellow flames which not only cause a deposit of carbon, but are highly inefficient for heating purposes.

With the burner of the present invention, however, the radiation is so active that there is a strong current of heat passing away from the burner which not only precludes blanketing of the burner, but also precludes a constant inrush of fresh air, producing complete combustion and proper heating.

Having thus fully described the invention, what I claim as new and desire to secure by Letters Patent is:

1. A heating element for broilers embodying a rigid, noninflammable and nonmetallic plate provided with flat faces and having parallel rows of perforations all of which perforations are of substantially the same size and through which gas is adapted to pass, and parallel ribs of hardened plastic mineral earth molded directly on to one face of the plate and positioned between successive rows of perforations, whereby gas issuing from the perforations is adapted to burn between the ribs and heat said ribs to a high temperature, so that the heat taken up by the ribs may be radiated. 80

2. A heating element for broilers embodying a rigid, nonmetallic and noninflammable plate provided with a plurality of parallel rows of perforations through which gas is adapted to pass, a plurality of ribs of hardened plastic mineral earth molded directly on the face of the plate and between successive rows of perforations, said plate being placed so that the ribs are in horizontal positions, whereby gas issuing from the perforations at the ribbed face of the plate, burns between successive ribs and the flame is deflected away from the face of the plate in such manner as to preclude the flames of one row of perforations from interfering with the proper combustion of the gas flowing from the superimposed rows of 105 perforations. 100

3. A heating element for broilers embodying a rigid, noninflammable and nonmetallic plate provided with a substantially flat face and perforated to permit the passage of gas 115 therethrough, and projections extending from the face of the plate and formed of hardened plastic mineral earth, whereby the flame from the burning gas is adapted to heat said projections to a high temperature so that the heat thus taken up by the projections may be radiated to effect the broiling operation. 120

4. A heating element for broilers embodying a rigid, noninflammable and nonmetallic plate provided with flat faces and having parallel rows of perforations through which gas is adapted to pass, and parallel ribs of hardened plastic mineral earth molded directly on one face of the plate and posi- 130

tioned between successive rows of perforations, whereby gas, issuing from said perforations, is adapted to burn between the ribs for the purpose of heating the same to a high temperature, so that the heat thus taken up by the ribs may be radiated to effect the broiling operation.

5. A heating element for broilers embodying a rigid, noninflammable and nonmetallic plate provided with flat faces and having parallel rows of perforations through which gas is adapted to pass, and parallel ribs of hardened plastic mineral earth molded directly on one face of the plate and positioned between successive rows of perforations, whereby gas, issuing from said perforations, is adapted to burn between the ribs for the purpose of heating the same to a high temperature, so that the heat thus taken up by the ribs may be radiated to effect the broiling operation, said ribs being provided with a roughened and uneven surface comprising relatively small tapering projections, which increase the superficial area of said ribs and increase its capacity to radiate the heat.

20 25

6. A heating element for broilers embodying a perforated face plate, a back plate

spaced from the face plate to form a gas chamber, a gas inlet to said chamber at the lower portion thereof, and a plurality of screens positioned transversely across the gas chamber for the purpose of retarding the flow of gas through the gas chamber and effecting a uniform distribution of said gas through all of the perforations.

7. A heating element for broilers embodying an upstanding face plate provided with spaced horizontal rows of perforations, substantially parallel rows of hardened plastic mineral earth molded on the forward face of the face plate intermediate the rows of perforations, a back plate spaced from the front plate to provide an intermediate gas chamber, a gas inlet at the lower part of the gas chamber, and foraminous partitions extending transversely of the gas chamber and in the path of the flow of gas upward through said chamber for the purpose of retarding the upward rush of gas and assuring its uniform distribution to all of the perforations.

In testimony whereof I have signed the foregoing specification.

MAX SCHEY.
